OTTO H. ESCHHOLZ, OF WILKINSBURG, PENNSYLVANIA, ASSIGNOR TO WESTINGHOUSE ELECTRIC & MANUFACTURING COMPANY, A CORPORATION OF PENNSYLVANIA

GAS FILLED TANK

Application filed October 6, 1932. Serial No. 592,888.

My invention relates to tanks or containers and it has particular relation to tanks adapted to contain a liquid and a blanket of inert gas above the liquid.

In the manufacture of tanks, of the character described, which are adapted to contain an oil-immersed electrical apparatus, such as transformers, circuit-breakers and the like, it has been customary in certain instances to provide breathing vents for the purpose of permitting the oil and air within the tank to expand and contract with changes in the temperature thereof.

Difficulty has been encountered with this type of container for the reason that the oxygen contained in the air that was admitted to the interior of the tank through the breathing vent, carried with it a certain amount of moisture, which mingled with the oil and decreased the dielectric properties thereof. Furthermore, the oxygen in the air admitted to the tank combined with the oil and caused the decomposition thereof.

The oxidation of the oil caused a viscous deposit or "sludge" that settled on the apparatus and not only retarded the radiation of heat therefrom but seriously impaired the circulation of the oil through the cooling system thereof. In the event that a short-circuit or an arc developed in the submerged apparatus, hydrogen and methane gases were liberated from the insulating oil and combined with the oxygen in the air within the tank to form a blanket of highly explosive gas over the insulating oil. If a spark occurred within this gas during a short-circuit, an explosion of considerable force resulted with the consequent danger to life and property adjacent thereto.

In order, therefore, to reduce this hazard, it has been suggested to seal the interior of the tank from the outside atmosphere, to provide suitable means for permitting the expansion and contraction of the oil through predetermined temperature ranges and to also replace the air contained in the tank by an inert gas. This suggestion, while eliminating the danger from explosion, presented the difficulty of replacing the air with gas and constructing the tank with hermetically

sealed seams and bolted cover connections, to prevent the subsequent escape of the gas from the tank and the dilution thereof by air leaking into the tank through faulty seams.

In its broadest aspect, an object of my invention is to utilize the deoxidizing properties of phosphorus, or metals of the alkaline earths, to extract the oxygen from the isolated atmosphere within a tank partially filled with a material that has a tendency to generate or liberate a gas or gases which, when combined with oxygen, produce an explosive mixture.

More specifically, an object of my invention is to provide a tank adapted to contain an oil-immersed electrical apparatus and an isolated atmosphere above the oil and which embodies a deoxidizing agent that is sealed within the tank for the purpose of removing the oxygen from the air and to leave a blanket of inert gas over the oil that has no tendency to cause the deterioration of the oil or to form an explosive mixture by combining with the gases given off by the oil.

A further object of the invention is to provide an apparatus of the character set forth, employing a deoxidizing agent for the purpose specified, which will be transformed, during the process of oxidization, into a hygroscopic oxide that will absorb any moisture that may be contained in the isolated atmosphere of the tank, subsequent to the closing thereof, and thereby preserve the dielectric qualities of the insulating oil.

With such objects in view, as well as other advantages which may be incident to the utilization of the improvement, the invention consists in the parts and combinations thereof herein-after set forth and claimed, with the understanding that the several necessary elements constituting the same may be varied in proportion and arrangement without departing from the nature and scope of the invention.

In order to make the invention more clearly understood, means are shown in the accompanying drawing for carrying the same into practical effect, without limiting the improvements, in their useful applications, to the particular constructions which, for the

purpose of explanation, are made the subject of illustration.

The single figure of the accompanying drawing is a vertical sectional view through a tank partially filled with an oxidizable oil and illustrating a deoxidizing and dehydrating agent disposed within the isolated atmosphere of the tank above the surface of the oil.

10 Referring to the drawing, a tank embodying my invention is shown as comprising a body portion 1, which is adapted to be partially filled with an oxidizable fluid 2, such as oil, within which an electrical apparatus (not shown) may be immersed. A main cover 3 is provided for the tank and is secured thereto in any preferred manner to prevent the outside atmosphere from obtaining access to the interior of the tank.

20 The main cover 3 of the tank is provided with the usual manhole 4, and a cover 5 therefor, by means of which access may be readily obtained to the interior of the tank. A receptacle 6 is suitably secured to the manhole

25 cover 5 and extends downwardly through the manhole 4 into the isolated atmosphere contained in the upper portion of the tank 1.

When the tank is installed for operation and the cover 3 is secured in place, a deoxidizing agent 7, preferably embodying phosphorus in cartridge form, is placed within the receptacle 6, and the manhole cover 5 is then bolted in place. The oxygen contained in the atmosphere sealed within the tank 25 above the oil is absorbed by the deoxidizing agent 7 leaving an inert nitrogen gas, which forms an isolated inert atmosphere over the oil. As the deoxidizing agent combines with the oxygen present in the original pocket of air, it is transformed into an oxide, such as phosphorus pentoxide, P_2O_5 , which is highly hygroscopic and absorbs any moisture that may be contained in the inert gas blanket.

40 By means of the above described construction, a very efficient gas-tight tank is obtained which embodies means for automatically generating an inert and relatively dry atmosphere within the tank subsequent to the closing thereof, thus avoiding the disadvantages hereinbefore enumerated.

I claim as my invention:

1. The combination with a casing for electrical apparatus adapted to be immersed in insulating liquid, and a space above said liquid for inert gas, of a liquid seal for isolating said space from the atmosphere under predetermined conditions and for permitting communication therebetween under other conditions, and means for removing oxygen from such air as may enter the tank through the liquid seal.

2. A casing containing an electrical apparatus, a body of combustible fluid in which said apparatus is immersed, and gases resulting from the combustion of material

other than said combustible fluid above said fluid body.

3. In combination, a tank, an insulating oil contained in the tank, electrical apparatus contained in the tank immersed in said oil, an atmosphere above the oil within the tank, a deoxidizing agent in contact with the atmosphere for coating with oxygen in said atmosphere to produce a hygroscopic oxide, thus producing an inert and substantially dry atmosphere within said tank.

4. In combination, a tank, an insulating oil contained in the tank, electrical apparatus contained in the tank immersed in said oil, a gaseous blanket above the oil comprising an atmosphere sealed within the tank, a deoxidizing agent in contact with said atmosphere for removing the oxygen therefrom, whereby the deterioration of the oil and the formation of an explosive mixture above the oil is prevented.

In testimony whereof, I have hereunto subscribed my name this second day of October, 1922.
